CLAIM

The ornamental design for a automatic light controller with sound and motion activation, as shown.

DESCRIPTION

FIG. 1 is a front perspective view without the switchplate of a automatic light controller with sound and motion activation showing my new design;

FIG. 2 is a side elevation view without the switch plate thereof;

FIG. 3 is a front elevation view without the switchplate thereof;

FIG. 4 is a rear elevation view without the switchplate thereof;

FIG. 5 is a top plan view without the switchplate thereof;

FIG. 6 is a bottom plan view without the switchplate thereof;

FIG. 7 is a front perspective view including the switchplate thereof;

FIG. 8 is a side elevation view including the switch plate thereof;

FIG. 9 is a front elevation view including the switchplate thereof;

FIG. 10 is a rear elevation view including the switchplate thereof;

FIG. 11 is a top plan view including the switchplate thereof; and,

FIG. 12 is a bottom plan view including the switchplate thereof;

The switch plate is omitted in FIGS. 1–6 for convenience of illustration.
